PLATE, CLAMP

Filed July 26, 1930

Inventor
CHARLES W. HARROLD

By His Attorney
Philip B. Rich

UNITED STATES PATENT OFFICE

CHARLES W. HARROLD, OF CLEVELAND, OHIO, ASSIGNOR TO HARRIS-SEYBOLD-POTTER COMPANY, OF CLEVELAND, OHIO, A CORPORATION OF DELAWARE

PLATE-CLAMP

Application filed July 26, 1930. Serial No. 471,049.

My invention relates to improved clamping mechanism for securing flexible sheets or plates in even and firm contact with a suitable support, such as a printing-press cylinder, and is particularly adapted for securing the rubber blankets as well as the zinc plates to the cylinders in offset printing presses, though it may be advantageously used in other types of presses.

The objects of my invention are, among other things, to provide a simple and novel clamp mechanism for such printing plates or blankets which shall be convenient to operate and which shall strain and hold the plate wrapped about the cylinder surface with a uniform tension so as to prevent any wrinkles or unevenness on the surface of the flexible blanket or plate whereby accurate printing is ensured.

A further object of my invention is to provide a plate-clamping mechanism of such a character that a small opening or gap in the cylinder will afford sufficient space for its location and manipulation while permitting an almost continuous printing surface on the cylinder by diminishing the width of the gap when the plate is in stretched printing position.

A further feature of my invention is the provision of an improved plate-clamp embodying the desired attributes of simplicity, efficiency and durability, and which will enable the flexible blanket or plate not only to be clamped to the cylinders and easily and quickly loosened therefrom, but also to have the longitudinal clamping shafts supported at several points along the cylinder gap to produce a rigid, uniform and effective clamping action with the adjusting mechanism conveniently located outside the zone of such printing blankets and plates wrapped about the cylinders.

With these and other objects in view, my invention comprises the construction, combination and arrangement of the various parts hereinafter described, and then particularly pointed out in the appended claims.

In the accompanying drawings, Fig. 1 is a front elevation of the press cylinder with the flexible blanket or plate wrapped about

the cylinder which is partly broken away to show my improved plate-clamp in its preferred form;

Fig. 2 is an enlarged detail view of one of the clamping shafts mounted in the cylinder;

Fig. 3 is a detail view on the line 3—3 of Fig. 2;

Fig. 4 is an end view of the left end of the cylinder in Fig. 1 partly broken away; and

Fig. 5 is an enlarged sectional view on the line 5—5 of Fig. 1.

Similar numerals refer to similar parts throughout the several figures.

Referring to the drawings, the press cylinder 6 is of the usual hollow construction having the peripheral cylindrical side-walls 7 integral with the ends 8 and 9 provided with the outwardly-extending bosses 10 and 11 which serve to support the cylinder 6 in the side-frames 12 and 13 of the press (Fig. 1). Extending longitudinally along the surface of the cylinder 6 is the cross-shaped slot 14 (Fig. 5) having the oppositely disposed rectangular recesses 15 and 16 enlarged throughout the body of the cylinder 6 within which recesses the plate-clamping mechanism proper is located.

The recesses 15 and 16 carry the longitudinal clamping shafts 17 and 18 respectively having their cylindrical surfaces ridged, roughened or knurled at 19 as shown in Figs. 1—3, and part of their cylindrical surfaces is cut away at 20 and 21 (Fig. 5) between which the ends of the flexible blanket or plate are inserted as shown in Fig. 5 at the beginning of the plate-clamping action.

The shafts 17 and 18 are rigidly supported by having their ends journaled in the cylinder ends 8 and 9, and also by having spaced apart bearings 22 cut away from the ridged or knurled surfaces 19 of the shafts 17 and 18. The bearings 22 rotatably contact with the supporting ribs 23 (three shown for each shaft 17 and 18 in Fig. 5) located in the recesses 15 and 16 which prevent the shafts 17 and 18 from springing apart when clamping the plate. The outer ends of the shafts 17 and 18 are squared (Fig. 4) to enable the shafts to be turned by a crank or wrench.

Means are provided to hold firmly the shafts 17 and 18 in plate-clamping position that are best shown in Figs. 1 and 4: On the left end of Fig. 1 the shaft 17 carries the ratchet 24 adjacent the cylinder end 8 which is engaged by the pawl 25 pinned to the end 8; in like manner the shaft 18 (on the right of Fig. 1) carries the ratchet 26 which is engaged by the pawl 27 pinned to the cylinder end 9 (also shown by dotted lines in Fig. 4).

10 I may also provide intermeshing gears 28 and 29 on the shafts 17 and 18, one of which is slidingly keyed to either of the ends of the shafts 17 and 18 (Fig. 4), so that one of the gears 28 and 29 may be slipped sidewise (shown by dotted lines in Fig. 1) out of mesh with its coacting gear in which case both ratchets 24 and 26 would be used to tighten the blanket or plate ends independently of the other. When the gears 28 and 29 are in mesh the tightening can be accomplished from either end of the cylinder 6 by rotating either shaft 17 or 18.

25 The rubber blanket or plate 30 having the ends 31 and 32 is wrapped about the cylinder 6 (Figs. 1 and 5) with the ends 31 and 32 inserted in the slot 14 and in close contact with the cut-away surfaces 20 and 21 of the shafts 17 and 18 respectively. As shown in Fig. 5 a thin metal strip 33 may be introduced between the blanket ends 31 and 32 to enable either end to be tightened independently of the other when the gears 28 and 29 are out of mesh since the interposed metal strip 33 will provide the necessary slippage between the opposed blanket ends 31 and 32.

30 In operation the shafts 17 and 18, after the ends 31 and 32 of the blanket or plate 30 are in adjusting position as shown in Fig. 5, are revolved toward each other so that the ridged or knurled surfaces of the shafts will close on the ends 31 and 32 and bite into the fabric of the rubber blanket 30 along the line of compression between the two shafts 17 and 18 which are rigidly and uniformly supported along their entire length by the spaced-apart bearings 22 revolving on the three-ribbed supports 23 thereby preventing the shafts 17 and 18 from springing apart. The ratchets 24 and 26 with their respective pawls 25 and 27 (with or without the intermeshing of the supports 23 thereby preventing the shafts 17 and 18 in tightened position.

35 This clamping action of the knurled shafts 17 and 18 may be applied to the flexible plates or rubber blankets of a printing-press, but is especially adapted to stretch and hold the rubber blanket on the press cylinder. My invention is not to be restricted to the precise details of construction shown since various changes and modifications may be made therein without departing from the scope of the invention or sacrificing the advantages derived from its use.

40 I claim as my invention:—

1. A plate-clamp for holding a flexible plate on its support comprising oppositely disposed coacting clamping shafts oppositely rotatable to grip and hold the plate ends interposed therebetween, each shaft being independently rotatable, detachable operative connections between the shafts to rotate same in unison, and separate means to lock each shaft in plate-holding position.

2. In combination, a printing cylinder 45 having a gap, a pair of coacting clamping shafts recessed in the gap and rotatably supported upon spaced-apart bearings within the gap, cut-away portions on the shafts between which the plate ends are interposed, the peripheral surfaces of the shafts being ridged or knurled to grip and hold the plate upon the rotation of the shafts in opposite directions, means for rotating said shafts in unison, separate means for rotating each shaft independently of the other, and means for locking each shaft in plate-holding position.

3. A plate-clamp for holding a flexible plate on its support comprising oppositely disposed coacting shafts oppositely rotatable to grip and hold the plate ends interposed therebetween, spaced-apart supports to bear on said shafts at a plurality of points, detachable operative connections between the shafts 50 to rotate same in unison, and separate means for locking each shaft in plate-holding position.

CHARLES W. HARROLD.
